UNITED STATES PATENT OFFICE.

ADOLPHE BESSAT AND LÉON LOUIS LIÉVENS, OF NANTERRE, FRANCE.

ROTARY DUPLICATOR.

Application filed January 12, 1924. Serial No. 685,806.

To all whom it may concern:

Be it known that we, ADOLPHE BESSAT, citizen of the Republic of France, residing at Nanterre, France, post-office address 16, Rue 5 du Vieux-Pont, and LÉON LOUIS LIÉVENS, citizen of the Republic of France, residing at Nanterre, France, post-office address 19, Rue du Vieux-Pont, have invented certain new and useful Improvements in Rotary Duplicator 10 tors, of which the following is a specification.

This invention relates to a development of the apparatus described in our prior application filed 21st September 1922.

15 The present construction is characterized by a novel arrangement of the printing cylinders, which are four in number and superposed in pairs, for the purpose of effecting two-colour printing on both side of a sheet. 20 The said construction differs from the apparatus described in the above-mentioned application because of the manner in which the upper cylinders are supported and because of certain other constructional details, all as 25 will hereinafter appear.

A constructional example of the duplicating apparatus according to the present invention is illustrated in the accompanying drawings in which:

30 Figure 1 is a side elevation of the duplicator fitted with four printing cylinders.

Figure 2 is a section on line A—B of Figure 1.

35 Figure 3 shows in elevation one of the pivoted levers supporting the upper printing cylinders.

40 Figures 4 and 5 are plans showing the motion-transmitting elements or clutch members in operative and inoperative position, respectively.

45 Figure 6 is an elevation of a duplicator according to this invention, fitted only with two superposed printing cylinders and suitable for printing on one face of a sheet or simultaneously on both faces.

Referring to Figures 1 and 2, the duplicator comprises four main elements which are the printing cylinders 1, 2, 3 and 4. In 50 the apparatus according to this invention these cylinders (of the type described in application No. 589,693, dated 21st September 1922, and referred to in the foregoing), are superposed in pairs and are provided each with a stencil pattern to be reproduced. The 55 said cylinders are however differently fixed

in position; the lower cylinders 2 and 4 are mounted on the frame 5 through the medium of split bearings 6 and 7 and the upper cylinders 1 and 3 are mounted on the pivoted supporting levers 8 and 9 through the medium of split bearings 10 and 11. Owing to these two levers 8 and 9, the upper printing cylinders 1 and 3 are also used as pressure cylinders. These levers serve moreover the further purpose of keeping up the rotation of the said upper cylinders 1 and 3 when the latter are out of contact with the lower cylinders 2 and 4. To this end, the said supporting levers 8 and 9 are pivoted at 12 on the frame 5, the pivot axis of each lever being coincident with the axis of the associated toothed wheel 13 (Figures 1, 3, 4 and 5). It may be clearly seen from Figure 4 that owing to this arrangement the upper cylinders are rotated through the medium of the toothed wheels 14 when the said cylinders are out of contact with the lower cylinders. The supporting levers 8 and 9 are provided with extensions or arms 15 and 16 (Figures 1, 2 and 3). The outer ends of the springs 17 and 18 are secured to the lower ends of the said arms, the inner ends of said springs being secured to the frame 5 so that the upper cylinders 1 and 3 are pressed against the lower cylinders 2 and 4.

The arms 15 and 16 may be moved with the aid of two sets of cams 19 and 20 actuated by means of handles 21 and 22, for the purpose of holding the upper cylinders 1 and 3 away from the lower cylinders 2 and 4 while the duplicator is being made ready for work. The duplicator is worked by means of the crank handle 23 wherefrom motion is transmitted to the various elements through the toothed wheels shown in chain lines. When the apparatus is operative the rollers 24 and 25 carried on the toothed wheels 26 and 27 come periodically into contact with the arms 15 and 16 of the pivoted supporting levers 8 and 9. The upper cylinders 1 and 3 are thus intermittently moved away from the lower cylinders 2 and 4, for the purpose of affording free passage to the stencil-fastening means 28 and allowing the sheet moved by the automatic feeder described hereunder to be placed in the desired position relatively to the printing cylinders so that it is picked up by the latter when they come in contact.

- again. The sheet is now gripped and advances between the two cylinders 1 and 2 to be printed a first time on both faces. The said sheet is now led through the medium of a guide plate 29 to the drying cylinders 30 and 31; it passes along between the same and reaches the two printing cylinders 3 and 4 between which it is provided on both sides with the complementary colour printing.
- 10 The sheet passes over a guide plate 32 and between the drying cylinders 33 and 34 and finally reaches a collecting tray (not shown). The drying rollers 33 and 34 belong to a group of elements supported on frame members 36 pivoted to the frame at 37 so that the said group of elements may be moved outwards when the printing cylinder 4 is to be removed. The frame members are held in position by two hooks 38.
- 15 20 The drying rollers 30, 31, 33 and 34 are similar to those described in our prior application hereinbefore referred to.
- A variety of printing may be carried out by means of the apparatus just described, e. g.:
1. Two-colour printing on both faces of a sheet;
2. One-colour printing on one face of a sheet and two-colour printing on the other;
- 30 3. One-colour printing on both sides of a sheet.
4. Two-colour printing on one side of a sheet.
- 35 5. One-colour printing on one side of a sheet.
- One, two or three printing cylinders are removed according to the kind of printing required, and if they are lower cylinders, they are replaced by rubber-faced pressure cylinders placed according to circumstances in one of the supports 39 and 40.
- 40 The operative connection between the cylinders and the driving mechanism may be removed to render the cylinders idle and for setting them in their correct relative position after they are clamped to the machine. To this end, the clutch mechanism illustrated in Figures 4 and 5 has an axially movable toothed wheel 14 which may be thrown, by means of the finger-piece 42, in and out of mesh with the motion-transmitting toothed wheels 13 and 41. Each of the printing cylinders 1, 2, 3 and 4 has a clutch mechanism of this type, operated by means of the finger-pieces 42, 43, 44 and 45 respectively. The movable wheel 14 is of course thrown into mesh with the other two wheels after the setting operation is completed.
- 50 55 60 The automatic feeder is similar to that described in our prior application No. 676,543, filed 23rd November 1923. The said feeder is suspended from the supports 54 and held in position by the clamping device 55 secured to the tie-rod 56 of the frame 5.

The automatic feeder is actuated off the toothed wheel 57.

As mentioned in the foregoing, Figure 6 illustrates a duplicator fitted with two superposed printing cylinders only and designed either for simultaneously printing on both sides of the sheet or for printing on one side thereof. To this end the lower cylinder is removed and replaced by a rubber-surfaced pressure roller or cylinder. This construction needs no further description, as it is replica, minus two cylinders, of the duplicator fully described in the foregoing.

Constructional modifications may be made to the above-described construction of the apparatus without departing from the invention.

We claim:

1. In a rotary duplicator, the combination of a pair of superposed, coacting elements, one of which is a printing cylinder mounted in vertically movable bearings; pivotally-mounted supporting levers connected with said bearings to shift the same when rocked and thereby move the cylinder away from its coacting element; a system of intermeshing gears for driving said coacting elements; and projections on certain of the gears in such system for periodically engaging and automatically rocking the levers.

2. In a rotary duplicator, the combination of a pair of superposed, coacting elements, one of which is a printing cylinder mounted in vertically movable bearings; pivotally-mounted supporting levers connected with said bearings to shift the same when rocked and thereby move the cylinder away from its coacting element; a system of intermeshing gears for driving said coacting elements; projections on certain of the gears in such system for automatically engaging and rocking the levers at regular intervals; and a manual device operative at will upon said levers to rock the same.

3. In a rotary duplicator, the combination of two pairs of superposed, coacting elements arranged in spaced, parallel relation, one element of each pair being a printing cylinder mounted in vertically movable bearings; a pair of pivotally-mounted supporting levers connected with each pair of bearings to shift the same when rocked and thereby move the cylinder away from its coacting element; a system of intermeshing gears connected with both pairs of elements to drive the same; and projections on certain of the gears in such system for periodically engaging and automatically rocking the levers.

4. In a rotary duplicator, the combination of two pairs of superposed, coacting elements arranged in spaced, parallel relation, one element of each pair being a printing cylinder mounted in vertically movable bear-

- ings; a pair of pivotally-mounted supporting levers connected with each pair of bearings to shift the same when rocked and thereby move the cylinder away from its 5 coacting element; a system of intermeshing gears connected with both pairs of elements to drive the same simultaneously; projections on certain of the gears in such system for periodically engaging and operating 10 both pairs of levers automatically at regular intervals; and a manual device associated with each pair of levers to engage and operate either pair at will independently of the other pair.
- 15 5. In a rotary duplicator, the combination of a pair of superposed, coacting elements, one of which is a vertically movable printing cylinder; a pair of supporting levers for said cylinder connected at one end therewith 20 and pivotally mounted intermediate their ends; means operative upon said levers to rock the same and thereby move said cylinder away from its coacting element; and a train of gears for rotating said cylinder and 25 including a gear at one end of the cylinder, and a gear for driving the first-named gear having its axis coinciding with the axis of pivotal movement of said levers, whereby the rotation of the cylinder may be continued while it is out of contact with its 30 said coacting element.
6. In a rotary duplicator, the combination of a pair of superposed, coacting elements,
- one of which is a vertically movable printing cylinder; a pair of supporting levers for 35 said cylinder connected at one end therewith and pivotally mounted intermediate their ends; means operative upon said levers to rock the same and thereby move said cylinder away from its coacting element; 40 a train of gears for rotating said cylinder and including a gear at one end of the cylinder, and a gear for driving the first-named gear having its axis coinciding with the axis of pivotal movement of said levers, whereby 45 the rotation of the cylinder may be continued while it is out of contact with its coacting element; and means for interrupting 50 at will the drive from the second-named gear of the train to the first-named gear thereof.
7. A rotary duplicator, according to claim 6, in which the interrupting means comprises a clutch carried by the adjacent lever and interposed between the second- 55 and first-named gears.
8. A rotary duplicator, according to claim 6, in which the interrupting means comprises an intermediate gear carried by the adjacent lever and shiftable laterally out of 60 and into mesh with the second- and first-named gears.

In testimony whereof we affix our signatures.

ADOLPHE BESSAT.

LEON LOUIS LIEVENS.
